A. COTTON

SECTIONAL HEADER

Filed Nov. 11, 1925

INVENTOR:
ALFRED COTTON, deceased.
BY BAKERWELL & CHURCH
ATTORNEYS.

UNITED STATES PATENT OFFICE.

ALFRED COTTON, DECEASED, LATE OF ST. LOUIS, MISSOURI, BY LAURA P. COTTON, EXECUTRIX, OF ST. LOUIS, MISSOURI, ASSIGNOR TO HEINE BOILER COMPANY, OF ST. LOUIS, MISSOURI, A CORPORATION OF MISSOURI.

SECTIONAL HEADER.

Original application filed August 4, 1923, Serial No. 655,667. Divided and this application filed November 11, 1925. Serial No. 68,375.

This application is a division of the application for patent that resulted in U. S. Patent No. 1,565,061, to Alfred Cotton, dated December 8, 1925.

5 The object of the present invention is to provide a sectional header, which, in addition to having the essential features and characteristics of the header described in U. S. Patent No. 1,565,060, to Alfred Cotton, 10 dated December 8, 1925, is provided in its sides with pockets for holding the packing that is used to caulk the joints between adjacent headers.

Another object is to provide a header of 15 the general type disclosed in the said Cotton Patent No. 1,565,060, which is of such design that the bulges on the front and rear sides of the header contain sufficient metal to eliminate the possibility of the header rupturing or cracking during the operation of deforming said bulges to produce tube seats and hand hole cover seats.

Figure 1 of the drawings is a perspective view of a boiler header that embodies the 20 present invention.

Figure 2 is a side elevational view of said header.

Figure 3 is an elevational view of the rear side of the header.

30 Figure 4 is a vertical sectional view of said header, taken on the line 4-4 of Figure 3; and Figure 5 is a horizontal sectional view, taken through two adjacent headers, illustrating the packing that is used to caulk the joints between said headers.

The header shown in the drawings is preferably constructed from a welded or seamless tube of cylindrical or oval shape in cross section, that is deformed by dies so as to produce a header of substantially rectangular shape in cross section, provided with two corrugated lateral sides, each of which is made up of a series of valleys 1 arranged in alternate relation with a series of ridges 2 and disposed diametrically opposite the valleys and ridges on the other lateral side of the header, a front portion that is provided with a group of relatively wide, flat faces 3 that extend transversely of the header and 45 a group of relatively narrow, flat faces 4 that lie between said wide faces 3, and a rear portion provided with a group of relatively wide, flat faces 3^a and a group of

55 relatively narrow, flat faces 4^a arranged in alternate relation. The flat faces 3^a and 4^a on the rear side of the header are provided with holes 30^a and 40^a for receiving the water tubes of the boiler in which the header is used, and the flat faces 3 and 4 on the front side of the header are provided with 60 hand holes 30 and 40 that are normally covered by hand hole plates or covers (not shown). In the particular form of the invention herein illustrated two tube holes are formed in each of the wide, flat faces 3^a 65 on the rear side of the header and two hand holes are formed in the flat faces 3 on the front side of the header, but this is not essential, as the seat faces on the front and rear sides of the header and the holes in said 70 seat faces can be disposed in various ways without departing from the spirit of the invention.

The flat faces on the front and rear sides of the header that contain the tube holes and 75 hand holes are inclined slightly to the vertical, as shown in Figure 4, so as to form tube seats and hand hole cover seats that are disposed at substantially right angles to the longitudinal axis of the boiler tubes, 80 each of the hand hole cover seats on the front side of the header being arranged slightly higher than the particular tube seat on the rear side of the header with which it co-operates so that the hand holes will be 85 arranged diametrically opposite the tube holes and in longitudinal alignment with the tubes, this feature of the header being illustrated clearly in Figure 4, wherein the dot and dash lines α indicate the center lines of 90 the boiler tubes and the center lines of the tube seats and hand hole cover seats on the front and rear sides of the header.

It will be noted by reference to the drawings that the valleys 1 in the lateral sides 95 of the header are formed by diametrically opposed, inwardly-pressed portions of the tube from which the header is constructed and that the ridges 2 on the lateral sides of the header are formed by diametrically-100 opposed portions of said tube that bulge laterally in opposite directions from the center line of the header. Also that the valleys and ridges on the lateral sides of the header are disposed in parallel relation with each 105 other, but are inclined slightly to the hori-

zontal, so as to extend in the same general direction as the tubes of the boiler. By referring to Figure 2 it will be noted that the portions on the front side of the header 5 that are located at the front ends of the valleys 1 bulge forwardly and that the portions on the rear side of the header that are located at the rear ends of said valleys bulge rearwardly, thus virtually forming groups 10 of transversely-disposed valleys on the front and rear sides of the header that lie between groups of transversely-disposed ridges or bulges on the front and rear sides of the header.

15 The flat faces on the front and rear sides of the header that constitute the hand hole cover seats and the tube seats are produced by forming indentations in the transversely-disposed valleys and bulges on the front and 20 rear sides of the header, as shown in Figures 1 and 3, the metal in these portions of the header being bent in such a way as to produce reverse bends or folds f at the ends of said flat faces, as shown clearly in Figure 25 1.

In order to prevent the metal in these portions of the header from being bent abruptly at such a sharp angle as to tend to cause the metal to rupture, the ribs on the side dies that form the valleys 1 in the lateral sides of the header are not disposed in absolutely parallel relation to the center lines of the co-operating flat faces on the front and rear sides of the header, represented by the dot and dash lines α in Figure 35 4, but, on the contrary, are disposed slightly out of parallel with said center lines, so as to produce bulges on the front and rear sides of the header that are of sufficient area 40 to permit said bulges to be indented or pressed inwardly to form the flat faces, without causing the metal at the ends of said flat faces to crack. To state it in another way, the center lines of the ribs on the side dies of the deforming apparatus are set at 45 a slightly greater angle to the horizontal than the center lines marked α in Figure 4, so as to produce bulged portions on the front and rear sides of the header that are of greater area and which contain more metal 50 than if the center lines of the ribs of the side dies were arranged in absolutely parallel relation to the center lines represented by the dot and dash lines α in Figure 4. Accordingly, the header that forms the subject-matter of this application is distinguished from the header described in the U. S. Patent No. 1,565,060, to Alfred Cotton, dated Dec. 6, 1925, in that the ridges and the valleys in the lateral sides of the 55 header are disposed at a slightly greater angle to the horizontal than the center lines of the boiler tubes, the result that is attained by constructing the header in this manner 60 being that the bulges on the front and rear sides of the header contain sufficient metal 65

to prevent them from cracking or rupturing when they are indented to produce hand hole cover seats and tube seats.

Another novel feature of the header that forms the subject-matter of this application is that it is provided in its lateral sides with pockets for receiving the packing that is used to caulk the joints between adjacent headers. Said pockets are formed by depressions 2^a in the ridges 2 on the lateral sides of the header and they are produced during the deforming operation by the natural tendency of the metal in the crowns of said ridges to cup up at the ends of the ridges when the opposed portions in 30 the sides of the tube are bent inwardly and when the intermediate portions in the front and rear sides of the header are pressed inwardly to form the wide, flat faces in 35 which the tube holes and hand holes are formed.

Having thus described the invention, what is claimed as new and desired to be secured by Letters Patent is:

1. A sectional header of substantially rectangular shape in cross section adapted to have a plurality of circulating tubes connected to same, said header consisting of a deformed metal tube provided on its lateral sides with diametrically-opposed, outwardly-bulged portions and diametrically-opposed valleys that are disposed at a slight angle to the circulating tubes, bulges on the front and rear sides of the header arranged in staggered relation to the outwardly-bulged portions on the lateral sides of the header, and tube holes and hand holes in the front and rear sides of the header.

2. A sectional header of substantially rectangular shape in cross section adapted to have a plurality of circulating tubes connected to same, said header consisting of a deformed metal tube provided on its lateral sides with diametrically-opposed, outwardly-bulged portions and diametrically-opposed valleys that are disposed at a slight angle to the circulating tubes, bulges and valleys on the front and rear sides of the header arranged in staggered relation with those on the lateral sides of the header, and flat seat faces in the bulges and valleys on the front and rear sides of the header provided with hand holes and tube holes.

3. A sectional header of substantially rectangular shape in cross section adapted to have a plurality of circulating tubes connected to same, said header consisting of a deformed metal tube provided on its lateral sides with diametrically-opposed, outwardly-bulged portions and diametrically-opposed valleys that are disposed at a slight angle to the circulating tubes, and angularly-disposed, flat seat faces on the front and rear sides of the header provided with holes and joined to the valleys in the lateral sides of

the header by folded or reversely-bent portions of the tube from which the header is constructed.

4. A sectional header of substantially rectangular shape in cross section adapted to have a plurality of circulating tubes connected to same, said header consisting of a deformed metal tube provided on its lateral sides with diametrically-opposed valleys and ridges, bulges on the front and rear sides of the header arranged in staggered relation to the ridges on the lateral sides of the header, hand holes and tube holes in the front and rear sides of the header, and pockets in the ridges on the lateral sides of the header for holding the packing material that is used to caulk the joints between adjacent headers.

5. A sectional header consisting of a hollow member of substantially rectangular shape in cross section constructed from a metal tube whose walls are bent in such a way as to form diametrically-opposed valleys and ridges on the lateral sides of the header and also flat surfaced seat faces on the front and rear sides of the header, hand holes and

tube holes in said seat faces, and depressions in the crowns of the ridges on the lateral sides of the header for holding the packing that is used to caulk the joints between adjacent headers.

6. A sectional header consisting of a hollow member of substantially rectangular shape in cross section constructed from a metal tube whose walls are deformed to produce diametrically-opposed ridges and diametrically-opposed valleys in the lateral sides of the header, said valleys being disposed at a slight angle to the longitudinal axis of the circulating tubes, depressions in said ridges that constitute pockets for receiving packing material, bulges on the front and rear sides of the header, hand holes and tube holes in the front and rear sides of the header, and flat seat faces in the front and rear sides of the header produced by indentations in the bulges on these portions of the header.

LAURA P. COTTON,
*Executrix de bonis non under the Will of
Alfred Cotton, Deceased.*
